UNITED STATES PATENT OFFICE.

UGO ANTONI, OF VIAREGGIO, ITALY.

BODY STRUCTURE FOR AERIAL AND LAND VEHICLES AND MARINE CRAFT.

Application filed February 8, 1927, Serial No. 166,755, and in Italy May 5, 1926.

The present invention relates to a system of construction for hulls and car bodies in general of a minimal resistance to their progress in fluids.

5 If the body of fishes is examined we see that the fore section is always strongly larger than in the remaining body progressively tapering towards the tail that is towards the axial propeller.

10 Besides this shape constant in all classes of fishes we note that in the bony fishes the opercles are placed in the largest section of the body and always consist of a very resistant substance and while they evidently serve 15 to protect the respiratory organs (gills or branchiae) they have another not negligible function.

In the reciprocating movement of the respiration the section of the fish in the zone of 20 the head augments intermittently by the action of the fluid flowing through the gills.

Owing to said shape the speed impressed to the fish by the tail propeller causes the fluid to suffer an abrupt side deviation, a strong depression consequently taking place in these 25 zones while the meeting of the fluid threads shifted by the head occurs in the main propeller that is in correspondence of the tail.

The ratio between the section, the length 30 and speed of a fish is constant, consequently short fishes have a strongly compressed form so that the fish tail propeller turns to act in a place adapted to obtain the highest efficiency that is in correspondence of the meeting 35 point of the fluid threads displaced by the fore section of the fish.

It is now evident that owing to the creation of two lateral zones in which the fluid has suffered a depression as above mentioned the 40 oscillations of the body will occur with a small force while the caudal fin is exposed to the full impact of the fluid, a maximum efficiency being thus realized by means of a minimal force.

45 It is further to be noted that the pectoral fins are constantly placed behind the opercles, said fins at will of the fish may receive the impact of the fluid at the beginning of the displacement caused by the opercles which besides 50 displacing more the fluid of the lateral zones to facilitate the penetration of the whole system owing to their rational distribution of elasticity transform the passive resistance into components directed towards the movement in addition to the propulsion of the caudal propeller.

The object of the present invention is derived from the above summary remarks to obtain the same effects in the hulls and car bodies in general while moving, that is a 60 remarkable diminution of the passive resistances.

The invention is diagrammatically illustrated in the accompanying drawings, in which:

Fig. 1 shows a plan view of the hull of a hydroplane,

Fig. 2 a plan view of hull of submarine boat,

Fig. 3 a torpedo, and

Fig. 4 is a plan view of body of aeroplane.

The offsettings or steps *a b* such as found in variable numbers of the point of the fins fulfill the same purpose by flexible plates *c*. The steps *a* have the function of opercles.

Plates *c* of flexible material are tapered from attachment to hull towards the back edge and may also be composed of variable length in order to give a decreasing elasticity so as to describe highly efficient curves under the resistance met with when in movement.

The deformation of said plates *c* besides removing the fluid from the lateral surface of the hull thereby decreasing the passive resistances, generate components for the decomposition of forces directed towards the movement and therefor useful.

Blades *c* applied to offsettings and steps in the outer lower part of hull have also the function to raise them to the surface of the water under high speeds, and said blades *c* may be operated by pilot.

The above described system may be used for any shape of hull or coach or cabin body, for dirigible propelled bodies, aerial and other 95 torpedoes, and any kind of propelling system.

The back part of the various structural forms may be provided with stabilizing plans, depth rudders, steering rudders, propellers, etc.

Having now particularly described and ascertained the nature of my said invention and in what manner the same is to be performed I declare that what I claim is:

1. In aerial, land and marine craft, a body having external offsets defining step-like formations, and flexible plates arranged along the sides of the body, and also located at the step-like formations.

2. In aerial, land and marine craft, a body having external offsets defining step-like formations, and flexible plates arranged along

the sides of the body, said plates being arranged in superposed layers.

3. In aerial, land and marine craft, a body having external offsets defining step-like formations, and flexible plates arranged along the sides of the body, said plates being arranged in superposed layers and of varying length and tapering from the point of attachment to the body towards the opposite ends.

4. In aerial, land and marine craft, a body having external offsets defining step-like for-

mations, and flexible plates arranged along the sides of the body, said plates being arranged in superposed layers and of varying length and tapering from the point of attachment to the body towards the opposite ends.

In testimony whereof I have hereunto signed my name.

UGO ANTONI.
